RUBBER STAMP INKING PAD

Horace E. Nichols and George Howlett Davis,
Detroit, Mich.; said Davis assignor to said
Nichols

Application February 17, 1949, Serial No. 76,926

6 Claims. (Cl. 118—264)

1

This invention relates to inking devices and, in particular, to ink transfer devices such as stamp pads and the like.

One object of this invention is to provide an ink transfer device, wherein the ink holding and transferring portion is composed substantially entirely of finely divided particles, such as powdered metal, the ink feeding up through the device by means of capillary attraction.

Another object is to provide an ink transfer device, including an ink pad made by powder metallurgy, wherein tiny particles of metal are pressed together to form a porous plate.

Another object is to provide an ink transfer device, as set forth in the preceding objects, wherein an ink reservoir is provided beneath the pad by forming recesses or passageways either in the pad or in the portion of the base adjacent the pad.

Another object is to provide an ink transfer device, as set forth in the preceding objects, wherein the base is provided with a sliding cover, which may be mounted in one position to expose the ink pad and in another position to conceal it and protect it.

Another object is to provide an ink transfer device, as set forth in the preceding objects, wherein the ink deposits only a thin film on the top of the pad and does not spread up the sides of the rubber stamp, thereby enabling the pad to be used for many thousand impressions or stampings before any appreciable change occurs in the density of the impression made by the stamp.

Another object is to provide an ink transfer device, as set forth in the preceding objects, wherein the all-metal construction of the pad gives a long wear and provides a flat even surface which uniformly inks the stamp when the latter is pressed down upon it.

Another object is to provide an ink transfer device, as set forth in the preceding objects, wherein the base beneath the ink pad is provided on its lower surface with minute capillary ink grooves radiating outward to the margin from a filling hole in the center, these grooves being preferably tapered and shallower toward their entrance portions, the ink flowing along the grooves during the filling operation toward an ink well channel around the edge, the ink being conveniently supplied from a collapsible tube having a nozzle fitting the filling hole.

Another object is to provide an ink transfer device, as set forth in the object immediately preceding, wherein the marginal breather pas-

2

sageways are provided to equalize the pressure on the ink resulting from temperature changes in the room where it is used, thereby preventing flooding after the device has stood overnight in a cold room which is then heated to a warm temperature.

In the drawings:

Figure 1 is a top-plan view of an ink transfer device, according to one form of the invention, 10 with the pad and base partly broken away to show the underlying structure;

Figure 2 is a vertical cross-section along the line 2—2 in Figure 1;

Figure 3 is a vertical longitudinal section along 15 the line 3—3 in Figure 2;

Figure 4 is a perspective view of the ink transfer device shown in Figures 1 and 2, with the cover thereof slid back partway from its protecting position;

20 Figure 5 is a cross-section through a modified ink transfer device, generally similar to Figure 2, but having ink reservoir recesses in the bottom of the pad;

Figure 6 is a cross-section through a further 25 modified ink transfer device, wherein the pad is provided with longitudinal ink passageways;

Figure 7 is a top plan view of a modified ink transfer device, with the cover, rim frame and ink pad successively broken away to disclose the underlying construction;

30 Figure 8 is a side elevation, partly in vertical section, along the line 8—8 in Figure 7;

Figure 9 is a vertical cross-section taken along the line 9—9 in Figure 7 at right angles to the vertical section shown in Figure 8;

Figure 10 is an enlarged fragmentary vertical section taken along the line 10—10 in Figure 12;

Figure 11 is a fragmentary vertical section along the line 11—11 in Figure 7;

Figure 12 is an enlarged fragmentary top plan view of one quarter of the ink reservoir lying beneath the metallic ink pad;

Figure 13 is a vertical section along the line 13—13 in Figure 12, taken through one of the division ridges between the ink grooves;

Figure 14 is a side elevation, partly in section, through the edge of the ink reservoir, taken along the line 14—14 in Figure 12; and

Figure 15 is an enlarged fragmentary vertical section similar to Figure 10, but showing a modification wherein the grooves are placed in the transfer pad rather than in the base.

Referring to the drawings in detail, Figures 1, 2 and 4 show an ink transfer device, generally 55 designated 10, according to one form of the in-

vention, as consisting generally of a base 11, an ink transfer pad 12 seated therein and a sliding cover 13 slidably mounted on the base 11. The cover 13 is of any suitable shape, the outline being rectangular and provided with longitudinal rectangular grooves 14 which serve to receive tongues or flanges 15 which extend inward from the opposite lateral edges 16 of the cover 13. The cover 13 has a top portion 17 bridging the edge portions 16 and serving to cover and protect the pad 12. At least one end of the cover 13 is open so as to permit the base 11 and its pad 12 to be slid into the interior of the cover 13. The base 11 and cover 13 are conveniently made of molded plastic material.

The base 11 is provided with a recess 18 (Figure 2), preferably having a flat bottom 19 and slightly inclined edges 20. By this means the pad 12 can be forced into the recess 18 and anchored therein by the resilience of the pad 12 and base 11. The base 11 (Figure 2) is provided with spaced parallel grooves 21 which serve as reservoirs to hold the ink with which the device is supplied. In order to hold the cover 13 yieldably against the base 11, a leaf spring 22 (Figures 1 and 3) is mounted in one of the grooves 14 and yieldingly and frictionally engages the adjacent rib or flange 15. In order to fill the reservoir groove or recesses 21 with ink, the grooves 21 are interconnected by a transverse groove or header 23. Opening into the header groove 23 is a threaded hole 24 closed by a screw plug 25.

The pad 12 is formed preferably of metal particles joined together by the conventional process of powder metallurgy, the process itself being well-known in the metallurgical art and, therefore, requiring no detailed description. According to this process, the particles of metal, preferably tiny spheres, are forced together in a die by means of a press, and are then sintered to unite them. Thus, the metal spheres are separated from one another by interstices of microscopic proportions, these interstices forming minute passageways through which the ink will climb by means of capillarity. One type of pad which has been found to work satisfactorily is formed of bronze particles united by being pressed together and sintered. The pad 12 has a substantially smooth flat extended working surface on its upper side as is self-evident from the drawings.

In the operation of the invention, the screw plug 25 is removed and a suitable ink is introduced therethrough, preferably by means of a pressure gun or syringe, so as to fill the passageways or grooves 21 with ink distributed thereto from the transverse header groove 23. When the ink emerges from the pores in the top of the pad 12 and the latter is suitably covered with a film of ink, the filling is terminated. The screw plug 25 is then re-inserted in the threaded hole 24 and the pad is ready for use.

The ink used with the present invention must not leave a residue which will clog the pores. It should also preferably be of a type which has a relatively low viscosity and also easily wets the metal particles of which the pad is constructed. Certain inks which are available on the market for use with ball-pointed fountain pens have been found satisfactory as they are sufficiently thin to flow readily by capillary attraction through the pores of the pad, they wet the metal particles and they do not clog the pores of the pad.

In the use of the invention, the cover 13 is slid off the base 11 in the manner indicated in

Figure 4, and slid back onto the base 11 in an inverted position as shown in Figure 2. This prevents loss of the cover 13, and also adds to the weight of the device so that it does not slide around too easily on a desk or table. The rubber stamp which is to be inked is pressed down upon the top surface of the pad 12 in the usual way and a thin coating of ink is transferred from the top of the pad 12 to the bottom surface of the rubber stamp. When the term "rubber" is employed herein, it is also understood that synthetic rubber or any elastic deformable material of rubber-like properties may also be used and is intended to be included.

From experience with the present invention, it has been found that many thousand impressions may be made with an ordinary rubber stamp with very little change in the density of the inscription made on the paper upon which the stamp is subsequently impressed. Many thousand more impressions may be made before the device requires recharging. The present ink transfer device operates as long as the ink is in contact with the pad and this occurs as long as there is any ink in the reservoir grooves 21. As rapidly as ink is removed from the top surface of the pad 12 by the rubber stamps, more ink flows to the top surface through the pores of the pad by means of the force of capillarity. Even though the ink is temporarily depleted from the center portion of the pad 12, other ink flows through the pores and automatically redistributes itself over the pad.

The modification shown in Figure 5 is generally similar to the form of the invention shown in Figures 1 to 4 inclusive, and similar parts are similarly designated. The pad 12 of Figure 5, however, is provided with grooves 26 in the bottom of the pad itself in place of the grooves 21 in the bottom of the recess 18. The grooves 26, like the grooves 21 will, of course, interconnect by a cross groove (not shown), similar to the transverse groove or header 23.

The operation of the modification is also substantially the same as that of the form of the invention shown in Figures 1 to 4 inclusive, and hence requires no repetition.

The modification shown in Figure 6 is also generally similar to the form of the invention shown in Figures 1 to 4 inclusive, and similar parts are also similarly designated. In this modification, the grooves 21 are omitted from the base 11, and the pad itself is provided with longitudinal passageways 27 which serve as reservoirs for the ink. These are also suitably interconnected by a transverse passageway (not shown) similar to the header groove 23 and leading to a filling aperture similar to the filling aperture 24 of Figure 1. The operation of this modification is likewise similar to that of the form of the invention shown in Figures 1 to 4 inclusive and hence requires no repetition.

While the present invention has been described particularly as regards its application for use with rubber stamp pads, it will also be evident that it may be used for other purposes where ink is to be transferred. The pad, for example, may be used for taking fingerprints, merely by placing the fingers upon the pad to coat them with a thin film of ink. The fingers may then be removed from the pad and pressed down upon the paper record sheet or card in the usual manner. The present invention provides a thinner film than the ordinary pad of textile material, hence requires less ink and, accordingly en-

ables the impressions made by the rubber stamp or fingers to penetrate more rapidly than with the conventional pads.

The ink transfer device of the present invention is a virtually indestructible pad which is substantially unaffected by atmospheric conditions, which is easily cleaned, which does not easily absorb foreign materials and which can be easily wiped off. Since the pad itself is of metal, it has a very long life and, hence, requires replacement very infrequently in comparison with the ordinary inking pads of textile material.

The modified ink transfer device, generally designated 30, shown in Figures 7 to 14 inclusive, consists generally of an ink reservoir base 31 upon which is superimposed a porous metallic ink transfer pad 32 around which extends a border frame 33, the whole being closed by a slideable cover plate 34. The ink transfer pad 32 is of similar construction to the ink pad 12 in that it is likewise formed of minute metal particles joined together by the conventional process of powder metallurgy, as described above in connection with the forms of the invention shown in Figures 1 to 6 inclusive. The pad 32 has a substantially smooth flat extended working surface on its upper side, as is self-evident from the drawings. The ink transfer device 30 has the improved advantages of causing the ink to flow more evenly throughout the ink transfer pad 32 as well as to prevent flooding of the pad by the ink as the result of changes of temperature.

The base 31 is preferably of molded synthetic plastic or other suitable material and consists of a central plate-like portion 35 having inner and outer circular flanges 36 and 37 (Figure 9) likewise having a central tapered opening 38 in a boss 39 and closed by a plug 40. This is for the purpose of filling the device with ink, as described below. The plate-like portion 35 is preferably of approximately rectangular outline and is surrounded by a depressed portion 41 forming an ink channel or well 42 extending entirely around the plate-like portion 35. The depressed portion 41 is surrounded on its outer edge by a downwardly-extending flange 43 which, with the flanges 36 and 37 provides strengthening of the base 31.

In order to provide additional strengthening, diagonal ribs 44 (Figures 7 and 11) are also molded into the base 31, radiating outward from the central circular flange 36 through the outer circular flange 37 to the peripheral flange 43. The outer flange 43 continues upward in a slightly inset vertical flange 45 providing an annular shoulder 46 which is approximately the thickness of the border frame 33 so as to be substantially flush therewith as described below.

The marginal flange 43 is provided with spaced rounded edge portions 47 (Figure 11) leading to internal bosses 49 thereon. These are engaged by corresponding projections 67 on the cover 34, as explained below, when the latter is slid beneath the base 31 in a manner analogous to the position of the cover shown in Figure 2. 65 Certain of the diagonal ribs 44 are provided with grooves 48 (Figures 7 and 11) for the passage of the projections 67.

The upper surface of the plate-like portion 35 is provided at its central area with a multiplicity 70 of frusto-conical protuberances 50 occupying a central recess or receptacle 51 of rectangular outline to which ink is supplied through the central filling opening 38. The protuberances 50 are very close together so that their interstices form 75

crevices 52 into which the ink is drawn and lodges by capillary action. Radiating outward from the central recess 51 are minute capillary ink grooves 53 which are of approximately V-shaped cross-section (Figure 10) and which are also inclined downward at their bottoms from a comparatively shallow depth at their inner ends (Figure 13) to a considerably greater depth at their outer ends. The capillary ink grooves 53 are separated from one another by flat-topped ridges 54, the sloping sidewalls 55 of which form the side walls of the grooves 53. The inclined side walls 55 on the opposite sides of each ridge 54 meet at their outer ends in an approximately 15 conical end surface 56 (Figure 12) and these, in turn, extend downward into the ink channel or well 42 in semi-cylindrical portions 57. Thus, the grooves 53 not only deepen from their inner ends to their outer ends, but they also widen in the same direction, being flared slightly as they proceed outward. The inner ends of the ridges 54 are similarly rounded as at 58 with frusto-conical ends having smaller radii of curvature because of the narrower widths of the grooves 53 20 at their inner ends.

The border frame 33 has a downwardly-extending marginal flange 60 which is joined to a stepped inner flange 61 (Figure 11) by a downwardly and inwardly inclined web portion 62. The flange 61 and the inner edge of the web 62 are provided with a groove 63 of right-angle cross-section which fits down over the outer edge of the plate-like portion 35 and at the same time presses down on the ink transfer pad 32 and holds it in position at its margins. The frame 33 is preferably joined to the base 31 by cementing the flanges 60 and 45 together (Figure 11). In order to prevent the flooding of the pad 32 by changes in atmospheric pressure beneath the cover 34 by changes in temperature, the border frame 33 is provided with a pair of bosses 64 having passageways 65 (Figure 9) extending from the space above the ink transfer pad 32 to the space 65a above the ink well or channel 42. In this manner, the central opening 38, the central recess 51 and the grooves 53 are always in atmospheric communication with the space above the ink transfer pad 32.

The cover 34 is provided with a plate-like top portion 66 having detent projections 67 molded on the underside thereof, these being adapted to pass through the grooves 47 and 48 when the cover 34 is removed from its position above the ink transfer pad 32 and replaced on the bottom 50 of the device, as described in connection with the operation. The cover 34 is of channel-shaped cross-section having side flanges 68 (Figure 9) terminating in inwardly turned ridges 69 which are seated in the space between the shoulder 46 (Figures 9 and 11) and the lower edge of the flange 60. The latter space, in effect, provides a groove for receiving and retaining the inwardly turned ridges 69. The projections 67 serve as yieldable detents (Figure 8) to releasably hold the cover 34 in its closed position by engaging the web portion 62 of the border frame 33 below its outer rim. The projections 49 on the underside of the flange 43 similarly serve to engage the detent projections 67 when the cover 34 is placed beneath the base 31.

In the operation of the modified ink transfer device shown in Figures 7 to 14 inclusive, the interstices 52 of the central recess 51 are filled with a suitable ink by removing the plug 40, as with a paper clip, and inserting the correspond-

ingly tapered nozzle of a collapsible tube containing the ink into the central tapered opening 38 of the boss 39. The operator squeezes enough of the ink through the opening 38 into the central recess 51 to fill it and the capillary ink grooves 53 with ink whereupon he removes the nozzle and inserts either the old plug or, preferably, a new plug 40. These plugs may consist of ordinary eyelets, hence are expendable.

The ink flows by the pressure created by collapsing the tube, through the radiating capillary V-grooves 53 to all portions beneath the porous metal ink transfer pad 32, surplus ink passing into the recess or channel 42 forming the inkwell 10 around the periphery. As the ink becomes absorbed and used up by repeated use of the pad, the surplus ink in the well or recess 42 will flow backward up the capillary ink grooves 53 by capillary attraction, aided by the tapered configuration of the grooves. We have found that the ink flows naturally toward the converging or narrower part of the channel by capillary attraction and that even though the ink in the inkwell 42 is exhausted, any portion of the ink remaining in the grooves 53 will flow toward the smaller or inner ends of the grooves. We have found that passageways of uniform width and depth with parallel sides will not move the ink inward in this manner by capillary attraction unless aided by gravity when the device is tilted. The tapered grooves, however, will even cause the ink to flow uphill at a slight inclination. In order for the ink to flow into the interstices between the protuberances 50 from the grooves 53, however, these interstices should be narrower than the inner ends of the tapered grooves 53 to prevent the ink from being drawn from the interstices into the grooves. This will not occur, however, if there is a continuous column of ink leading to a larger cross-section of the groove, that is, one wider than the width of the interstices. When the ink column in the grooves 53 flows nearer the center to a point where the rearward end of the column lies in a cross-section of the groove which is narrower than the width of the interstices between the protuberances 50, the flow ceases unless the column is reconnected to a wider portion of the groove or to the inkwell 42 itself by supplying it with more ink.

These effects can be readily demonstrated by the use of a thin liquid, such as alcohol, which moves faster up the grooves 53 than does the ink or other liquids of higher viscosity.

Moreover, we have observed that the bottom surface of the metallic ink transfer pad 32 does not always fit snugly down upon the flat top ridges 54 between the capillary ink grooves 53, but frequently leaves a slight clearance. This narrow gap, however, has a beneficial effect in distributing the ink, particularly when all of the ink has been exhausted from the inkwell 42 and the columns of ink in the capillary ink grooves 53 have their rearward ends disposed inward from the outer ends of the grooves 53, namely inward from the inkwell 42. Due to the tapered configuration of the capillary ink grooves 53, these columns of ink which are now disconnected from the inkwell channel 42 will nevertheless continue to supply ink to the outer portions of the pad since ink tends to flow backward from the rearward ends of the ink column toward the inkwell channel 42, this flow occurring in the narrow clearance space between the tops of the ridges 54 and the bottom surface of the porous metallic pad 32. A slight clearance, of the order 75

of a 32nd of an inch, is left between the flange or skirt 61 and the outer edge of the plate-like center portion 35 of the base 31.

Furthermore, the construction of the inkwell 42, as shown at the right-hand side of Figure 8, is such that leakage is prevented and flooding eliminated even if the device is stored or carried in an inverted position or up on edge. If the device is inverted, the chamber of rhomboidal cross-section shown at the upper right-hand corner of Figure 8 will still hold the ink without leaking or flooding, whereas if the device is turned up on edge, the lower portion of this same chamber will hold the ink without leaking.

The modified ink transfer pad of Figures 7 to 14 inclusive will not flood overnight with ink even though the room in which it is located cools down to a low temperature in winter during the night and is heated up to a warm temperature during the day. This action alters the pressure above the ink pad 32 due to the contraction of the air as it cools down, and, without special provision to counteract it, would suck the ink up to the side of the pad 32. The little air passageways 65 (Figure 9) at the sides of the frame 33 serve to equalize the pressure between the inkwell or recess 42 and this in turn equalizes the pressure at the outer ends of all of the grooves 53 because it extends entirely around the central portion 35 of the base 31. The oblong shape of the central portion 35 also assists in preventing flooding since the ink will reach the inkwell 42 more quickly through the shorter grooves 53 than through the longer ones, the ink in the channel 42 reaching the outer ends of the longer grooves 53 directly.

In addition to serving as air passageways to prevent flooding, the passageways 65 also serve as limiting points in preventing over-filling the device 5 with ink. When the ink, in flowing outward from the central hole 38 reaches the passageways 65 it is time for the operator to cease further filling attempts. The air chambers or spaces 65a should be larger than the passageways 65 so as to prevent the raising of ink from the ink well 42 by capillarity.

The modification shown in Figure 15 is similar in principle and mode of operation to that shown in Figures 7 to 14 inclusive. In the modified construction of Figure 15, however, the base 70 corresponding to the base 31 of Figure 10 has a smooth upper surface 71 whereas the ink transfer plate or pad 72 has on its bottom surface 73 a pattern of converging V-shaped capillary ink grooves 74 similar to the pattern shown in Figure 13 and similarly leading to protuberances (not shown) in the center of the bottom surface 73 of the plate 72. In other words, the modification of Figure 15 merely reverses the position of the capillary ink groove and protuberance pattern by placing it on the underside of the ink transfer plate or pad rather than on the upper side of the base. The mode of operation of the modification of Figure 15 is substantially the same as that of the form of the invention shown in Figures 7 to 14 inclusive and hence requires no repetition.

What I claim is:

1. A rubber-stamp inking pad comprising a base structure having a cavity in the upper side thereof, a sintered porous powdered metal plate having a substantially smooth flat extended working surface composed of a multiplicity of minute metallic particles, an ink reservoir disposed beneath the top of said plate, said ink reservoir forming a part of said cavity, and means

for securing said ink reservoir to said plate in abutting relationship therewith, said particles engaging one another and having minute capillary passageways therebetween and a cover structure slidably engaging said base structure, one of said structures having a longitudinal groove in an edge thereof and the other structure having a projection slidably engaging said groove, said cover structure having side members extending adjacent the sides of said base structure and forming a recess of sufficient depth to receive said base structure either when said cover structure is positioned above or below said base structure.

2. A rubber-stamp inking pad comprising a base member having a cavity in the upper side thereof, a sintered porous powdered metal plate composed of a multiplicity of minute metallic particles secured in said cavity, said particles engaging one another and having minute capillary passageways therebetween and a cover member slidably engaging said base member, one of said members having a longitudinal groove in an edge thereof and the other member having a projection slidably engaging said groove and a spring contact device yieldably mounted on one of said members frictionally engaging the other member.

3. A rubber-stamp inking pad comprising a base structure, a sintered porous powdered metal plate member having a substantially smooth flat extended working surface superimposed on said base structure, said base structure having an ink conduit disposed at the periphery of said plate member, an air chamber between said ink conduit and said plate member, and an air passage-way extending between said air chamber and the space above said plate member, and means for securing said plate member to said base structure.

4. A rubber stamp inking pad comprising a base member, a sintered porous powdered metal plate member having a substantially smooth flat extended working surface superimposed on said base member and composed of a multiplicity of minute metallic particles engaging one another and having capillary ink pasageways therebe-

tween, one of said members having therein a central ink receptacle with a multiplicity of minute capillary ink grooves radiating outward from said receptacle, and means for securing said plate member to said base member.

5. A rubber stamp inking pad comprising a base member, a sintered porous powdered metal plate member having a substantially smooth flat extended working surface superimposed on said base member and composed of a multiplicity of minute metallic particles engaging one another and having capillary ink passageways therebetween, one of said members having therein a central ink receptacle with a multiplicity of minute capillary ink grooves radiating outward from said receptacle, said grooves being tapered inwardly toward said receptacle, and means for securing said plate member to said base member.

6. A rubber stamp inking pad comprising a base member, a sintered porous powdered metal plate member having a substantially smooth flat extended working surface superimposed on said base member and composed of a multiplicity of minute metallic particles engaging one another and having capillary ink passageways therebetween, one of said members having therein a central ink receptacle with a multiplicity of minute capillary ink grooves radiating outward from said receptacle, said grooves increasing in depth outwardly from said receptacle, and means for securing said plate member to said base member.
